AIR CONDITIONING APPARATUS

Edward L. Hart, Abington, Pa., assignor to Philco Corporation, Philadelphia, Pa., a corporation of Pennsylvania

Application March 17, 1948, Serial No. 15,383

4 Claims. (CL 62—140)

1

The present invention relates to refrigerating apparatus and, particularly, to air conditioning apparatus of a compact and unitary type, and to a novel mode of disposing of the condensate which normally results during operation of such apparatus.

In air conditioners, and particularly in apparatus of the type commonly referred to as "single room coolers," it is of substantial importance that the overall dimensions of the apparatus or unit be as small as possible. Achievement of this end has presented problems of considerable complexity, especially in view of the relatively large capacity which is desired in present day units of this kind. Basically, the refrigeration circuit employed in such units is well known, and the measure of public acceptance accorded apparatus of this type depends to a substantial degree on reducing its overall dimensions to the smallest possible compass; it being important, however, that such reduction be accomplished without sacrifice of either capacity or flexibility of operation, and with adequate provision for disposal of the condensate which results from contact of moisture laden air with the evaporator.

It is the primary object of my invention to provide a room cooling unit which is unusually small and compact, and in which those constructional features, from which flow the compactness, result in a substantial improvement in the efficacy of the moisture removing apparatus.

To the foregoing ends, the invention contemplates the provision of refrigerating or air conditioning apparatus of the type including evaporator and condenser elements, or coils, and means for forcibly circulating air in heat exchange relation with said coils, and in which the coils have such novel disposition with respect to the air circulating means as both to minimize the overall dimensions of the unit and to improve the moisture removal characteristics of the apparatus. Among the more important advantages of the unit are the following:

A. The relative disposition of elements contemplated by the present invention facilitates reduction in size of the apparatus.

B. Due to the novel angular relationship between the face of each coil and the air stream directed thereagainst, uniformity of air flow through the entire coil is achieved, as each fin "peels off" a layer of air and directs it through a corresponding section of the coil.

C. Uniformity of distribution of the condensate (derived from the evaporator) over the entrance or confronting face of the condenser is

2

insured, thereby increasing the evaporation rate. In this connection, it is to be understood that the evaporation takes place from the surface of the condenser and, therefore, the greater the surface that is wetted, the greater will be the evaporation rate. It will be evident that there is not sufficient heat present in any representative small portion of the condenser to provide adequate vaporization, if considerable condensate is concentrated in the region of said small portion.

D. Large droplets of water entrained in the condenser air stream are broken-up into a very fine mist, thus insuring against transmission of such droplets through the condenser and to outdoors—where staining of the wall, pluvious effusions upon subjacent itinerants, or like disadvantages may result.

The manner in which the foregoing objects and advantages are realized, together with others which will occur to those skilled in the art to which the invention appertains, will be understood from a consideration of the accompanying drawings forming a part of this disclosure, and in which:

25 Figure 1 is a somewhat diagrammatic plan view of air conditioning apparatus incorporating the concepts of the present invention;

Figure 2 is a sectional view of the lower portion of the apparatus, the view being taken along the line 2—2 of Figure 1;

Figure 3 is a view, partly in section and partly in elevation, and illustrating the apparatus as viewed in the direction indicated by the line 3—3, applied to Figure 1; and,

35 Figure 4 is an elevational view, on a greatly enlarged scale, showing the angular relationship between the condenser air stream and a fragmentary portion of the face of the condenser, and illustrating an advantageous action which takes place during removal of condensate.

Now making more detailed reference to Figure 1, in which there is illustrated air conditioning apparatus comprising a preferred embodiment of the present invention, it will be seen that the apparatus, or unit, comprises a casing, designated generally by the reference numeral 10, which casing encloses a refrigerating system including a motor-compressor 11, a condenser 12, an evaporator 13, and associated conduits through the agency of which said compressor, condenser and evaporator are coupled in series flow circuit.

These conduits include a discharge line 14, through which compressed refrigerant is delivered to the condenser 12, a feed line 15 which, as shown, may advantageously comprise a continu-

ously open restricted connection through which liquified refrigerant is fed to the evaporator for expansion therein. As is illustrated at 18, a strainer is preferably included in the feed line, and a suction conduit 17—a portion of which is provided with thermal insulation—serves to return the volatilized refrigerant to the compressor 11. Disposed in generally axial parallelism with the above-described sealed system is air moving apparatus including a motor 18 and a pair of blowers 19 and 20 which, respectively, are adapted to cause circulation of air in heat exchange relation with the evaporator 13 and the condenser 12. The blowers are housed in scroll structures, shown at 19a and 20a, respectively, and which structures are cooperable with partitioning elements, as now described.

Centrifugal blowers are preferably employed, not only because of capacity and efficiency considerations, but also because they afford greater 20 directional control of the air stream than is achievable with propeller type fans.

As indicated at 21, the cabinet is provided with a partition serving to divide the same into an evaporator chamber 22 and a condensing chamber 23. That portion of the cabinet which comprises the evaporator chamber (the portion lying to the left of dashed line 24, in Figure 1) is adapted to extend into a room or zone the air of which is to be conditioned, while that section of the cabinet lying to the right of said dashed line extends outwardly of the room, preferably through a window opening thereof.

The evaporator chamber 22 is, in turn, subdivided by means of a partition 25, into a section 35 housing the blower and scroll assembly 19—19a, and a portion within which is disposed the evaporator 13. The mouth 26 of scroll 19a extends through partition 25 and into position to direct air against one face of the evaporator 13. Suitable air ingress and egress openings indicated at 27 and 28, respectively, provide for circulation of room air into the casing 10, through a filter shown at 29, thence into the scroll structure 19a, from whence the air is forcibly circulated, by blower 19, in heat exchange relation with the evaporator 13 and redelivered to the room or space to be conditioned through the aforesaid egress opening 28. Similarly, the condensing chamber 23 is subdivided by partitioning elements shown at 30 and 31 to provide three sub-compartments one of which houses the compressor 11 and the blower motor 18, another the blower and scroll assembly 20—20a, and within the third of which is disposed condenser 12. The condensing unit is cooled by outside air flowing into the chamber 23 through either or both of the inlet openings shown at 32 and 33. As shown by the arrows indicative of air circulation, the air flowing into chamber 23 is delivered to scroll 20a and directed through condenser 12 by blower 20, finally being delivered to the outside atmosphere through a port represented at 34 which latter is provided with suitable louvers, as designated at 34a, in Figure 3. The primary paths of air circulation, and the functions performed by the resultant heat exchange will be understood without further explanation. However, it is to be noted that a certain amount of the outside air introduced through the inlet opening 33 may be mixed with the recirculated air passing in heat exchange relation with the evaporator, as will now appear.

As best seen in Figure 2, evaporator 13 has its lower surface supported within a pan-like struc-

ture 35, which latter is elevated somewhat above the floor 36 of the air conditioning apparatus. It is to be understood that the above-mentioned partition 25 extends upwardly from the pan-like member 35 and that, as is indicated by arrows appearing in both Figures 1 and 2, air flowing inwardly through opening 33 may be passed beneath the pan 35, through a filtering screen 37 and introduced into that chamber which houses the evaporator blower. In this latter chamber such outside air is mixed with recirculated air flowing in through egress opening 27, and the resultant mixture is forced through evaporator 13 and delivered to the room.

15 As thus far described, and with especial reference to the components of the air conditioning apparatus and to the functions performed thereby, the unit is more or less conventional in nature and its broad principles of operation are now well known.

In particular accordance with the present invention, and as will now be set forth, the relative disposition of certain of these components with respect to the two primary paths of air movement, and the angular disposition of said components within the air conditioner housing, are novel and particularly advantageous in that there results an unusually small and compact unit, as well as a substantial improvement in the efficiency of the moisture removing apparatus described hereinafter.

20 In this connection, it is to be noted that both the evaporator and condenser elements, or coils, are so angularly positioned, with respect to their associated blowers, as to result in uniformity of distribution of the moving air over the confronting faces of the coils, and consequent advantages both from the standpoint of a considerable reduction in the dimensions of the unit and in that a substantial improvement is effected in the moisture removal characteristics thereof.

25 Firstly, and making reference to the condenser and its associated blower, by way of example, it is seen that the condenser is so angled with respect to the direction of movement of the air flowing from blower assembly 20—20a that the projected length of the rear face of said condenser, on the cross-sectional width of the air stream leaving the mouth 38 of scroll 20a, is substantially equal to said width. Thus the air stream blankets the face of the condenser, and impinges obliquely thereagainst at an angle such that side portions of the condenser fins are struck. The importance of this oblique impingement is discussed further, hereinafter. The rear face of evaporator 13 is similarly oriented with respect to the air stream flowing from blower assembly 19—19a.

30 In arrangements commonly employed heretofore, the heat exchange coils were so disposed that the air flowing therethrough was directed at said coils along a line substantially normal to one face of the coil. That is, the major axis of the heat exchange coil was commonly disposed in right angular relation with respect to the direction from which air impinged upon the coil. Now with such prior structures, it is necessary to space the face of the coil from the mouth of the blower a considerable distance, this distance being sufficiently great to render one dimension of the air conditioning unit substantially equal to the dimension of the novel unit along partition 21, as seen in Figure 1. On the other hand, 35 in such prior structures, due to the aforesaid right angular relationship between the coils and

their associated blowers, the other coordinate dimension (that dimension represented by the width of the unit as illustrated in Figure 1) was very considerably in excess of the comparable dimension in the apparatus of this invention. Considered from another point of view, the coil disposition contemplated by the present invention is achieved without materially increasing one of the major overall dimensions of the apparatus, while at the same time considerably reducing the other coordinate major dimension and, concurrently, insuring uniformity of distribution of the impinging air over the heat exchange coils. This coil disposition involves novel angularity with respect to corner portions of the housing, as well as obliquity with respect to the impinging air stream.

In other known devices, the fan has been so disposed as to direct air in a stream paralleling one face of the coil, an angled baffle being used to redirect the air toward said face. Here again results have been unsatisfactory, in that the air, due to its momentum, was largely concentrated in that region of the coil which is most removed from the fan or blower. Attempts were made to meet this problem by the addition of so-called "splitters," which channelled the air into separate streams, each of which was directed at a corresponding zone of the coil face. However, such expedients increased the cost of the apparatus and did not eliminate concentration of air within the more remote region of each of the separate channels.

In short, while a variety of air flow arrangements have been available, none has yielded the uniformity of distribution available with the apparatus disclosed and claimed herein, and most such arrangements have resulted in relatively large and cumbersome apparatus.

As set forth, *supra*, such uniformity of air distribution results in a corresponding uniformity of the manner in which the condensate (derived from the evaporator) is distributed over the condenser. Prior to a more particularized consideration of this aspect of the invention, however, the condensate-collecting apparatus will be described.

As will be understood, normal operation of the unit results in accumulation of considerable condensate formed by virtue of contact of moisture-laden air with the evaporator 13; since, during such contact, the temperature of the air is reduced below the dew point. This moisture flows downwardly through the evaporator 13 and is collected in the above-mentioned pan-like member 35 (Figure 2) from whence it is delivered, through a pipe 39 to the vicinity of condenser 12. From said pipe the moisture flows downwardly and accumulates around the lower portion of condenser 12, as is indicated at 40, in Figure 3. The partition 31 cooperates with a second pan member 42 (Figure 2) to confine the moisture to the vicinity of the condenser. The lower portion of the condenser comprises a horizontally disposed coil loop 43 and a plurality of short fins 44 terminating below the main overlying fin structure. As will be appreciated, the loop 43 contains hot refrigerant delivered from the compressor through the agency of discharge line 14, and heat from such hot refrigerant is delivered to the condensate within pan 42 thereby vaporizing a portion of said condensate, the resultant vapor being carried off from the unit by the air stream flowing from blower 20.

Frequently, such removal of condensate does not occur at a rate equal to the rate at which

condensate is formed at the evaporator, and provision must be made to take care of the unusually high humidity conditions which occasion this result. To this end, the partition 31 is provided with an aperture 45 through which excess condensate may flow into a pan 46 which underlies the scroll 20a. When moisture has accumulated in the pan 46 to the level of the scroll, that is the level indicated at 47, moisture is drawn upwardly through aperture 48, provided in the lower portion of scroll 20a, and is entrained substantially uniformly throughout the cross-section of the air stream directed toward the condenser 12, in known manner. Such entrained moisture is, of course, forced outwardly through the scroll mouth 38 and impinges obliquely upon the angled confronting face of condenser 12.

As a result of the aforesaid angularity, and as clearly illustrated in Figure 4, each of the condenser fins 49 "peels off" an elemental layer from the air stream impinging upon the condenser, each elemental layer then being redirected by the fins 49 and thus caused to flow through the condenser and be expelled to the atmosphere through egress opening 34.

In contradistinction to the arrangements of prior practice, the moisture entrained with the air stream does not pass directly through the condenser—resulting in disadvantages indicated above—but first strikes the fins 49 in the manner shown in Figure 4. The velocity of the impinging air and therefore of the entrained moisture is considerable, and the relatively large droplets entrained in the moving air stream are broken-up into a very fine mist, by virtue of the impingement and the evaporation taking place at the surface of the condenser. The resultant mist, or vapor, flows through the condenser and is delivered to the outside atmosphere.

It is a feature of the described apparatus that the entrained condensate is uniformly distributed over the face area of the condenser rather than being concentrated in a relatively small portion of the condenser, as would be the case if the direction of air impingement were normal with respect to the major axis of the condenser structure. As will now be understood, there is not sufficient heat present in any elemental portion of the condenser to provide adequate vaporization, if considerable condensate is concentrated in the region of said portion. However, with the apparatus of the present invention, there results uniform distribution of the condensate, rather than concentration thereof, and a corresponding increase in the vaporization rate.

From the foregoing description, it will now be understood that apparatus incorporating the concepts of the present invention is characterized by a high degree of compactness, and that the relative disposition of components—which makes it possible to realize such compactness—results both in more effective use of the heat exchange surfaces of the evaporator and condenser, and in substantially improved moisture removal characteristics.

I claim:

1. An air conditioner or the like, comprising: a generally rectangular housing; an evaporator element within said housing and so disposed as to extend angularly across one corner of the housing; a condenser element within said housing and so disposed as to extend angularly across an adjacent corner of the housing; each of said elements including a plurality of fins defining parallel passages through the element, air pro-

7
pelling means disposed within another corner portion of said housing and operable to direct a stream of cooling air in heat exchange relation with said condenser element; and second air propelling means disposed in the other corner portion of said housing and operable to direct a stream of air to be cooled in heat exchange relation with said evaporator element, both said evaporator and said condenser elements having such angular disposition with respect to the air stream flowing in heat exchange relation therewith that the air impinges against side portions of said fins and is redirected thereby and caused to flow through said parallel passages.

2. In air conditioning apparatus or the like: 15 a housing; an evaporator disposed within said housing; a condenser disposed within said housing and having a substantially flat face; blower means within said housing for forcibly directing a stream of air against the said face of said condenser; means providing for exit of the air stream from said housing immediately following contact of said air with said condenser; and means for delivering condensate derived from the evaporator to said blower means and for entraining droplets of said condensate in said air stream substantially uniformly throughout the cross-section thereof, said condenser face having at least one dimension considerably in excess of any right angular cross-sectional dimension 30 of said air stream, and said condenser being so angularly disposed with respect to the direction of movement of said air stream that the projection of the said one dimension upon a cross-sectional dimension of the air stream—in a plane normal to the direction of movement thereof—is substantially equal to said cross-sectional dimension, whereby to insure substantially uniform distribution of the entrained condensate over said face.

3. In air conditioning apparatus or the like: 40 a housing; an evaporator disposed within said housing; a condenser disposed within said housing including a substantially flat face and a plurality of fin elements arranged in general parallelism and with their major axes extending in right angular relation with respect to said flat face; means for passing a stream of air in heat exchange relation with said condenser; means for delivering condensate derived from the evaporator to said last-mentioned means and for en-
